US00D485271S

(12) **United States Design Patent** (10) Patent No.: **US D485,271 S**
Kamegi (45) Date of Patent: ** Jan. 13, 2004

(54) **COMPUTER KEYBOARD**

- (75) Inventor: **Mikio Kamegi**, Kawasaki (JP)
- (73) Assignee: **Kabushiki Kaisha Toshiba**, Tokyo (JP)
- (**) Term: **14 Years**
- (21) Appl. No.: **29/171,541**
- (22) Filed: **Nov. 25, 2002**
- (51) LOC (7) Cl. **14-02**
- (52) U.S. Cl. **D14/392**
- (58) Field of Search D14/391-396;
D18/1, 2, 7; 178/17 A, 17 C; 235/145 A,
145 R; 200/5 A, 5 R, 6 A, 6 R; 341/22,
23; 345/160, 168; 400/472, 479, 484, 486,
488, 489, 492
